fig. 4

To all whom it may concern:

Be it known that I, Carl Reynolds, a citizen of the United States and a resident of Birmingham, in the county of Oakland and State of Michigan, have invented a new, original, and ornamental Design for an Automotive Electrical Testing Unit, of which the following is a specification, reference being made to the accompanying drawings, forming a part thereof.

In the drawings:

Figure 1 is a substantially front perspective view of an automotive electrical testing unit showing my new design.

Figure 2 is a top plan view of said testing unit.

Figure 3 is an end elevation view of said testing unit.

Figure 4 is a substantially front perspective view of said testing unit with the lead access door open.

Figure 5 is an end elevation view of said testing unit with said lead access door open.

I claim:

The ornamental design for an automotive electrical testing unit, substantially as shown and described.
